CLAIM

The ornamental design for a hot dog cooker, as shown
and described.

DESCRIPTION

FIG. 1 is a front perspective view of a hot dog cooker
showing my new design;

FIG. 2 is a front elevational view thereof;

FIG. 3 is a side elevational view thereof, the other side
being a mirror image;

FIG. 4 is a top plan view thereof;

FIG. 5 is a rear elevational view thereof;

FIG. 6 is a perspective view of the hot dog cooker in
open condition with the cover spaced above the lower
portion; and

FIG. 7 is a sectional view taken along lines 7—7 of
FIG. 6.
